(57) CLAIM

The ornamental design for a folder as shown and described.

DESCRIPTION

FIG. 1 is a front view of a folder showing our new design; FIG. 2 is a rear elevation view thereof; FIG. 3 is a top plan view thereof; FIG. 4 is a bottom plan view thereof; FIG. 5 is a right side elevation view thereof; FIG. 6 is a left side elevation view thereof; FIG. 7 is an enlarged view thereof taken at line 7 in FIG. 6; FIG. 8 is an enlarged sectional view thereof taken at line 8-8 in FIG. 7; FIG. 9 is an enlarged sectional view thereof taken at line 9-9 in FIG. 7; FIG. 10 is a top perspective view of FIG. 1; FIG. 11 is another top perspective view in a partially inserted upper state; and, FIG. 12 is another perspective view in a fully inserted state. The evenly spaced broken lines are directed to environment. The dot-dash broken lines depict the bounds of the enlarged and cross-section views and form no part of claimed design.

1 Claim, 12 Drawing Sheets
